SLIDING DOOR

James W. Greig, Detroit, Mich., assignor to Woodall Industries, Incorporated, Detroit, Mich., a corporation of Michigan

Application December 17, 1953, Serial No. 398,719

3 Claims. (Cl. 20—35)

This invention relates to improvements in sliding doors, closures, panels or the like.

The invention relates to sliding doors of the general character illustrated in my patent on Sliding Door Assembly 2,659,939, issued November 24, 1953, and assigned to the assignee of this application.

The sliding door construction illustrated in such prior application comprised a door consisting of a rigid panel provided along each upright margin with a split tube reinforcement extending along over the margin of the panel and secured thereto. This tube serves not only to reinforce and rigidify the panel so that it can serve its intended purpose but it also finishes and protects the margin of the door and its opposite ends provide a supporting mounting for roller or hanger assemblies which support the door for sliding movement. Such tubes were commonly formed of metal and were so shaped that they not only extended along over the upright margin of the door panel and grippingly engaged the same but they also projected laterally away from the face of the door on both sides of the door. Each tube exhibited a diameter substantially greater than the thickness of the door panel.

In many places where such doors are used it is desirable that the door exhibit a flush outer face, namely an outer face wherein the outer surface of the door panel itself is substantially flush with the outer face of the tubular marginal reinforcement.

An object of this invention is to provide a door of the character described wherein the tubular reinforcement which extends along over each upright margin of the panel is so shaped and so secured to the door panel as to provide the door with a flush outer face.

The tubular reinforcement is so constructed that it serves its intended purpose of protecting and surrounding the upright margin of the door to which it is attached and further provides a supporting mounting for the roller and hanger hardware used on the door and also the tube is so secured to the door that the outer face of the tube is approximately flush with the outer face of the door so as to present a neat and attractive appearance and facilitate sliding movement of a plurality of doors relative to each other.

A meritorious feature of the invention is that the split tube which is secured to the margin of the door is so constructed that attachment of the tube to the door margin may be easily and conveniently accomplished and the tube when secured to the door panel grippingly engages the panel so as to maintain its position thereupon.

The tube is generally rectangular in cross section and the split extends along one linear corner of the tube and one margin of the tube wall at the split is interlocked with a cooperating margin of the panel so as to hold the edge of the panel within an interior seat provided in the tube. The opposite margin of the tube at the split resiliently engages the panel so that the panel is grippingly held between the two margins of the tube at the split.

2

The construction of the tube and arrangement of the split therein is such that the side wall portion of the tube which overlies the outer face of the door panel is held snugly in abutment therewith so that the door exhibits a substantially flush outer face.

Another meritorious feature is that in a tube of the character above described with the split disposed along one linear corner that portion of the interior wall of the tube opposed to the split is so shaped as to provide a recess which receives and embraces the edge of the panel thereby holding the tube against tilting or dislocation with respect to the panel.

Other objects, advantages and meritorious features will more fully appear from the following description, claims and accompanying drawings, wherein:

Fig. 1 is a view of an elevation of a door frame provided with two sliding doors embodying the invention;

Fig. 2 is a vertical sectional view taken along line 2—2 of Fig. 1 showing the outer margin of the door in broken away elevation and the trackways in section;

Fig. 3 is a horizontal sectional view taken on line 3—3 of Fig. 1; and,

Fig. 4 is an end elevation of the tube and that marginal portion of the panel which is to be inserted therein showing the same prior to their assembly together.

This invention relates to the door per se rather than to its support or mounting; and the upper and lower trackways and the particular hanger employed form no part of the instant invention. Certain of these are claimed in my co-pending application Serial Nos. 432,856 and 417,309, filed May 27, 1954 and March 19, 1954, respectively. The same is true as to the illustration of the embodiment in Fig. 1 where two sliding doors only are shown. It is apparent the invention herein claimed might reside in a single door or in a number of doors that might be associated together.

The door of the invention comprises a rigid door panel 10 and a split tube 12 which is adapted to be received over and secured to a vertical margin of the panel 10. This tube provides rigidity and strength for the door. It also finishes off the margin and serves as a mounting for upper and lower roller assemblies in the manner illustrated in other applications. In Fig. 1 two of these doors indicated as A and B are illustrated as disposed within the door opening defined by a frame 14. Such door opening might be provided with a lower trackway such as indicated by the numeral 16 in Fig. 2 and an upper trackway indicated by the numeral 18 in Fig. 2. The lower trackway defines two channels 20 and 22. A guide plate or roller 24 secured to the bottom of the door is adapted to ride within such trackway channels 20 and 22. The door of Fig. 2 is provided with an upper hanger 26 provided with a roller 28 supported to travel within a channel track 30 of the upper track element 18.

The door panel 10 may be formed of plywood composition fiber board such as Masonite or any suitable material or assembly of materials built up to constitute a rigid panel structure. The edge of the panel is shown as beveled at 32 and as provided with a channel 34 in one face which channel extends parallel to the edge of the panel.

The split tube is illustrated as generally rectangular in cross section. It may be formed of metal or the like. It is split along one linear corner as shown in Figs. 3 and 4. That side wall portion 36 of the tube which defines one margin thereof along the split is shown as folded over upon itself as at 38. Such side wall portion is not only spaced laterally from the opposite side wall portion 40 which defines the opposed margin of the split but terminates short of the side wall portion 40. The side wall portion 40 is turned over as at 42.

That side wall portion of the tube which is opposed to the split is so shaped as by providing a bead 44 that such bead and the side wall portion 36 of the tube define therebetween a groove or channel adapted to receive the edge of the panel 10 when the marginal portion of the panel is inserted through the split of the tube, all as shown in Fig. 3. The beveled edge 32 of the panel facilitates the insertion thereof.

It is understood that the side wall portion 36 is tensioned inwardly and that portion of the tube opposite to the side wall 36 is tensioned toward such side wall 36, all as shown in Fig. 4. When the panel margin is inserted through the slit into the tube the side wall portion 36 is held yieldingly against the outer face of the tube and the fold 38 is received within the channel 34 of the panel. The side wall portion 40 of the tube is held yieldingly against the opposite face of the panel so that the tube is grasped between its two margins at the split and the edge of the tube is held to its seat within the channel formed between the rib 44 and the side wall portion 36 by virtue of the fact that the fold 38 is engaged within the channel 34 of the panel. As shown the outer margin of the tube is provided with two ribs not only rib 44 but rib 44a which serves to rigidify the tube and also to give such outer margin a uniform appearance.

What I claim is:

1. In a sliding door, a rigid door panel, a tube substantially rectangular in cross section provided with a split extending along one linear corner, said split tube extending along over one margin of the panel with the marginal portion of the panel disposed within the split and with the edge of the panel seated against that side wall of the tube opposed to the split, said side wall of the tube opposed to the split shaped to receive and embrace the edge of the panel, said tube having one side wall portion adjacent to the split lying flat against the adjacent face of the panel, the opposed side wall portion of the tube disposed spaced from its adjacent face of the panel, that side wall of the tube opposite to the side wall against which the edge of the panel is seated having a marginal part bearing resiliently against the adjacent face of the panel, and one of the marginal edges of the tube at the split interlocked within the face of the panel holding the

edge of the panel to its seat against that side wall of the tube opposed to the split.

2. A door comprising, in combination, a rigid planar door panel, a tube substantially rectangular in cross section provided with a split extending along one linear corner, said tube received over a marginal portion of the panel with such marginal portion extending through the split in the tube and with one side wall of the tube lying flat against the adjacent face of the panel and with the edge of the panel seated against that side wall of the tube opposed to the split, that side wall of the tube opposed to the side wall against which the edge of the panel is seated having a marginal portion bearing resiliently against the adjacent face of the panel holding the panel snugly against the first-mentioned side wall of the tube, said last-mentioned and said first-mentioned side walls of the tube tensioned toward each other, one of said tensioned side walls of the tube having its edge urged into the adjacent face of the panel holding the edge of the panel toward its seat against the tube wall opposed to the split and interlocked with the panel resisting withdrawal of the tube away from the edge of the panel.

3. A door as defined in claim 2 characterized in that the side wall of the tube provided with the edge which interlocking engages the face of the panel and holds the edge of the panel to its seat against the tube is the first-mentioned side wall of the tube and the face of the panel adjacent to said side wall is provided with a groove in which said edge of the side wall of the tube is seated and interlocked to hold the edge of the panel against that wall of the tube opposite to the split, and said wall of the tube opposite to the split is provided with a groove adjacent to the first-mentioned side wall of the tube within which groove the edge of the panel is seated.
